UNITED STATES PATENT OFFICE

2,514,783

ELECTROMAGNET

David Mohrlock and Helge Johnson,
Chelsea, Mich.

Application June 28, 1946, Serial No. 679,917

1 Claim. (Cl. 294—65.5)

1 Our invention relates to tools and more particularly to an electro-magnet.

The object of our invention is to provide an electro-magnet adapted to remove parts of axle shafts lodged in the differential gear housings of automobiles or trucks, without dismantling the differentials.

Another object of our invention is to provide an electro-magnet having a core made from a soft steel tube and equipped with a jacket of non-magnetic material.

Other objects of our invention may appear in the following specification describing our invention with reference to the accompanying drawing illustrating a preferred embodiment of our invention.

It is however to be understood that our invention is not to be limited or restricted to the exact construction and combination of parts described in the specification and shown in the drawing, but that such changes and modifications can be made which fall within the scope of the claim appended hereto.

In the drawing

Figure 1 is a side view of the electro-magnet according to our invention.

Figure 2 is a sectional view taken on the vertical longitudinal center plane of the electro-magnet shown in Figure 1.

Figure 3 is a sectional view taken on line 3—3 in Figure 2, and

Figure 4 is a sectional view taken on line 4—4 in Figure 2.

Referring now in detail to the drawing the electro-magnet according to our invention has a core 10 consisting of a soft steel tube. At a distance above the lower end of the core 10 a hole 11 is provided in one side of the tube. A second hole 12 extends through the wall of tube 10 on the same side as the first hole 11 at a distance above the first mentioned hole. The two holes are arranged at an angle in the wall of the tube so that they incline downwardly in outward direction.

An insulated electric wire 13 enters the tube 10 at its top end and extends through the lower hole 11. It is then wound around the soft steel tube 10 forming the coil 14 of the electro-magnet. The wire enters the tube 10 again through the upper hole 12 and extends upwardly through the tube, as shown at 15 in Figure 2.

At its lower end the soft steel tube 10 is provided with an inside thread and a brass plug 16 has an outside thread adapted to engage the inner thread of the soft steel tube 10, so that the

2 lower end of said tube is closed to prevent oil, grease, dirt, etc. from entering the tube.

A hollow cylindrical jacket 17 surrounds the soft steel tube 10 and extends from the upper end 5 thereof to and over the lower hole 11 in said tube. This jacket 17 is preferably made from a non-magnetic material such as brass. Its inner diameter is large enough, so that the jacket surrounds also the coil 14 on the core tube 10. The 10 lower end of the jacket is bent inwardly, as shown at 18, to protect the wire coil 14 from oil, grease, dirt and the like.

At the upper end a hollow cap 19 of non-magnetic material is arranged between the jacket 17 and the tube 10. The upper wall 20 is provided with a centrally located hole 21 having rounded walls permitting the wire 13 and the return wire 15 to extend therethrough. The hollow cap 19 has on its upper end a circumferential flange 22 20 abutting the upper edge of the cylindrical jacket 17.

A pin 23 extends through the wall of the jacket 17 and the wall of the hollow cap 19 to secure the latter in place.

25 The wire 13 and return wire 15 can be connected by any preferred conventional means to a source of electricity, so that the core tube 10 is energized by the current flowing through the coil 14. The connecting means and the source of electricity do not form any part of our invention and are therefore neither shown nor described.

The above description shows clearly, that the electro-magnet according to our invention is of 35 very simple construction, but can be used very efficiently to remove broken metal parts from the differential gear housing of a car or truck or any other place, which is not easily accessible, without dismantling or disassembling the differential 40 or the like.

The jacket 17 of non-magnetic material protects the apparatus against any damage caused by contact of the sides of the electro-magnet with an axle housing.

45 Having described our invention we claim as new and desire to secure by Letters Patent:

An electro-magnet for removing metal objects from an enclosed space, such as a vehicle rear axle housing, comprising an elongated tubular 50 core having two longitudinally spaced-apart holes in one end portion thereof, said holes extending from the outer surface of said core into the bore thereof, an insulated, electrically-conductive wire extending through the bore of said core from one end thereof and through one of said holes, said

wire being wound about said core and passed through the other of said holes into said bore and extending out of said bore at said one end of said core to provide an electro-magnetic coil around said core between said holes, an elongated, tubular jacket of non-magnetic material surrounding said core and said coil from said one end of said core to the end of said coil remote therefrom and providing a protective casing for said electro-magnet, a hollow cap of non-magnetic material surrounding said one end of said core within said jacket to support the corresponding end of said jacket on said core, said cap having a rounded hole therein for the passage of said wire therethrough, and a plug of non-magnetic 15

material threaded into the end of said bore opposite said one end of said core.
